UNITED STATES PATENT OFFICE.

JOHN S. FINCH, OF BRIDGEPORT, CONNECTICUT, ASSIGNOR TO THE SINGER MANUFACTURING COMPANY, A CORPORATION OF NEW JERSEY.

SEWING-MACHINE.

1,196,939.

Specification of Letters Patent. Patented Sept. 5, 1916.

Application filed April 7, 1913. Serial No. 759,346.

To all whom it may concern:

Be it known that I, JOHN S. FINCH, a citizen of the United States, residing at Bridgeport, in the county of Fairfield and State of Connecticut, have invented certain new and useful Improvements in Sewing-Machines, of which the following is a specification, reference being had therein to the accompanying drawings.

10 This invention relates to improvements in sewing machines for overcasting loose threads and thread ends by blind-stitching, as in the finishing of buttonholes, and has for its object to provide an improved machine of this type, to which end the various operations are effected through independent chains of connections leading direct from the main shaft of the sewing machine to the functional elements.

20 Referring to the drawings, Figure 1 is a view in front side elevation of the present construction, the frame or cloth-plate and bracket arm being shown in section to better illustrate the arrangement and relative action of the parts carried by and actuated from the main or driving shaft, the loop-taker, its guide-bracket and driver being omitted; Fig. 2 an underside view of Fig. 1, showing the frame in full lines; Fig. 3 a plan view of the cloth-plate and the throat or needle plate, the front and back slide plates being omitted to better illustrate the stitch-forming movements of the needle and co-acting loop-taker; Fig. 4 a front end elevation of the improved machine, the frame being shown in section to better illustrate the transversely arranged movements of the needle; Fig. 5 a rear side elevation of the machine, the frame being broken out to illustrate the mounting of the feed-dog-carrying bar; Fig. 6 a rear end elevation of Fig. 4; Figs. 7, 8 and 9 front edge, plan and rear edge views, respectively, of the throat or needle plate and attached needle-guard-carrying bar; Fig. 10 perspective views of the needle-guard-carrying lever and needle-plate bracket detached from the throat-plate; Fig. 11 a detail view of the needle-guard-actuating lever; and Fig. 12 a side elevation of the stop cam carried by the tight pulley.

30 Referring to the figures, the sewing machine frame comprises the cloth or bed plate 1 provided at its front and rear ends with

downwardly extending plates 2 and 3, respectively, and at its front and rear sides with similar plates 4 and 5, respectively, said plates being preferably formed integral with the bed-plate and at their lower edges provided with feet or rests, as 6, said bed-plate being provided with the usual bracket arm comprising the standard 7 and arm bracket 8.

The main or driving shaft 9 is mounted in suitable bearings, as 10, depending from beneath the bed-plate, and at its rear end is provided with loose and tight pulleys, 11 and 12, respectively, and hand wheel 14.

15 represents a horizontally arranged gear-shaft mounted to rotate in suitable bearings, as 17, and provided with a bevel gear 16, the axis of said gear-shaft being arranged parallel with but slightly out of line with the axis of said main shaft. The adjacent ends of the respective shafts are 75 operatively connected by a variable motion mechanism comprising the crank 18 carried by the main shaft, crank 19 carried by the gear-shaft and variable motion link 20 for operatively connecting said crank members. 80 The present variable motion mechanism is the same as that common to lock-stitch sewing machines generally wherein the loop-taker is given but a single rotation to one complete actuation of the needle-carrying bar.

21 represents a vertically arranged loop-taker-driving shaft provided at its upper end with a loop-taker driver 22 and mounted to rotate in suitable bearings formed in the 90 bracket 23 secured by screws, as 24, to the underside of the bed-plate, the shaft 21 being provided with a bevel gear 25 which meshes with the gear 16, thus transmitting rotary movements from the main shaft 9 95 to the loop-taker 26, which latter is provided with the usual bobbin-case 27 containing a mass of bobbin-thread (not shown). In the present construction the loop-taker 26, its guide-bracket 28 and the driver 22 are substantially the same in construction 100 and relative action as those represented by United States patent to Wheeler and Dial, No. 328,165, dated October 13, 1885.

29 represents a shaft-crank formed integral with the main shaft, and 30 a shaft-crank connection operatively connecting said main shaft with the crank 31 carried by the

Referring to the figures, the sewing machine frame comprises the cloth or bed plate 1 provided at its front and rear ends with

- needle-bar-actuating rock-shaft 32, the latter being mounted in bearings 33 and 34 formed in the depending brackets 35 and 36, respectively, and secured to the forward 5 end of said rock-shaft is a crank 37 pivotally connected to one end of a needle-bar-actuating link 38, the opposite end of the latter being pivotally connected to a needle-bar stud collar 39 secured upon the needle-bar
- 10 40 carrying the needle 41, thus transmitting from the main shaft to said needle-bar stitch-forming movements in the direction of its length.
- The needle-bar 40 is mounted in bearings 15 42 and 43 formed in the arms 44 and 45, respectively, of the rocking needle-bar frame 46, which latter is fulcrumed upon an eccentric bolt 47 passing through the plate 5 and secured by screw 48 in a bearing hub 20 49 forming a part of the bracket-plate 50 secured by screws, as 51, to the depending bracket 35.
- 52 represents a needle-vibrating lever fulcrumed on a stud 53 threaded into the base-plate and at one end provided with a cam follower 54 which tracks grooves, as 55, of a switch cam 56 carried by the main shaft, the opposite end of the lever 52 being pivotally connected to a needle-bar-vibrating 30 link 57 which in turn is pivotally connected to the needle-bar frame 46 by a stud screw 58 threaded into the arm 44 of the frame 46, thus transmitting rocking movements from the main shaft to said frame.
- 35 59 represents a feed-cam provided with a groove 60 (shown in dotted lines only, Figs. 1 and 2) and secured by screws, as 61, to the main shaft 9, and 62 a feed rock-shaft lever provided at one end with a cam roller 40 63 which tracks the groove 60, the opposite end of said lever being secured by a pinch screw 64 upon a feed rock-shaft 65 mounted to oscillate on pintle bearings, as 66, said feed rock-shaft being provided with arms 67 45 and 68 between which is pivotally suspended the feed-dog-carrying bar 69 provided with the feed-dog 70, the contour of the groove 60 being such as to give to the feed-dog feed movements, and 71 represents a feed-dog lift cam suitably secured upon the gear-shaft 15, the periphery of said cam acting on a stud 72 secured in the feed-dog-carrying bar 69 to effect vertically arranged movements of said feed-dog, thus transmitting from the 55 main shaft to said feed-dog feed and feed lift movements.
- It is to be understood that the present feeding mechanism comprises the commonly employed four-motion feed.
- 60 73 represents an eccentric carried by the main shaft, and 74 an eccentric connection, one end of which encircles said eccentric, its opposite end being pivotally connected with a crank arm 75 fast on the bender-carrying-bar-actuating-rock-shaft 76, which latter is

provided with a second crank arm 77 pivotally connected with one end of a link 77' whose opposite end is fulcrumed on a stud 78 formed integral with a sleeve 79 loose on the bender-carrying bar 80, the latter being 70 mounted to move vertically in suitable bearings located in the head 81 of the arm bracket and carrying at its lower end the fabric-bender 82.

Upon the bender-carrying bar 80 is 75 mounted a spiral spring 83 which at one end abuts against the lower end of the sleeve 79, its opposite end being seated against the collar 84 secured by screw 85 on the bar 80. The collar 84 is provided with an extended 80 portion 86 forked to receive the cloth-presser-carrying bar 87 (the outer prong 88 only being shown, see Fig. 4), said forked extension acting to hold the bar 80 against accidental axial movement. Adjacent to the 85 opposite end of the sleeve 79 there is secured upon the bar 80 by screw 88' a second collar 89 for limiting the sliding movements of said sleeve when acting to lift the fabric-bender from engagement with the material 90 being acted upon, the downward movement of said sleeve causing the effective end of the fabric bender to come in contact with the fabric, which movement is controlled to compress the spring 83, thus causing the 95 bender to be held in contact with the fabric until the sleeve in its upward movement again comes in contact with the collar 89, thus transmitting oppositely arranged vertical movements from said main shaft to said 100 fabric-bender.

As in earlier constructions, the cloth-presser-carrying bar 87, provided with a cloth-presser 90, is mounted in suitable bearings formed in the head 81 and normally 105 held depressed by a spring 91 seated upon a lift collar 92 provided with an extended portion 93, which latter, in the absence of other means, is acted upon by the presser-bar-lifting lever 94 to move the presser vertically.

95 represents a throat or needle plate suitably secured in the bed-plate, and at its upper side provided with a groove 96 into which the fabric is forced by the action of 115 the fabric-bender when the machine is actuated to form stitches, 97 an opening for the reception of the feed-dog, and 98 an opening for the needle-guard.

100 represents a needle-plate bracket 120 pivoted at one end on a fulcrum pin 101 secured in the needle-plate, its opposite end being secured against accidental movement by a screw 102 threaded into a depending portion 103 of the needle-plate, said bracket 125 being provided with a needle-opening 104.

105 represents a needle-guard-carrying bracket provided with a needle-guard 106 and pivoted at one end upon the pin 101, a spring 107 normally acting to hold said 130

bracket down upon the stop 108 forming a part of the bracket 100.

For controlling the effective action of the needle-guard 106 there is employed a needle-guard-actuating lever comprising a tubular shaft 109 from which projects an arm 110 provided with a cam roller 111, and an arm 112 provided with an adjusting screw 113 and securing screw 114, said tubular shaft 109 being mounted on a fulcrum pin 115 suitably secured in the bracket 23, a cam 116 carried by the loop-taker-driving shaft 21 acting, through the adjusting screw 113 coming in contact with the depending lug 117 of the bracket 105, to give to said needle-guard vertical movements, and the contour of said cam is such as to cause the needle-guard 106 to properly support the needle at the time the latter is about to pierce the fabric.

Power is transmitted from the supply to the machine through suitable connections, and for properly controlling such transmission of power there is employed a stop-motion mechanism comprising a vertically movable plunger 118 mounted in suitable bearings formed in a rocking frame 119 pivotally suspended upon pintle screws 120 secured in a bracket 121 which, in turn, is suitably secured to the standard 7, a spring 122 normally acting to hold said plunger in its depressed position. The frame 119 has formed integral with it an arm 123, to the outer end of which is pivotally attached one end of a link 124, its opposite end being pivotally connected with a rod 125 which passes down through the bed-plate and is at its lower end acted upon by a suitable manually controlled treadle (not shown) to rock the frame 119 in the direction indicated by the arrow *t*, Fig. 1, or in a direction to connect the tight pulley 12 with the source of power, a spring 126 normally acting to hold said frame at its limit of movement in the direction opposite that indicated by said arrow.

127 represents a stop-motion cam carried by the tight pulley and provided with an incline 128, cam wall 129 and notch 130, in which latter the lower end of the plunger is seated when the machine is at rest. The stop-motion mechanism herein employed is substantially the same as that illustrated and described in United States patent to G. S. Hill, No. 541,276, dated June 18, 1895, to which reference may be had.

131 represents a cloth-presser-bar-actuating lever pivoted by screw 132 upon the bracket arm, and at its forward end operatively connected with a lug 133 forming a part of the lift collar 92, its opposite end being pivotally connected to one end of a link 134 whose opposite end is secured in like manner to the arm 123, from which it will be obvious that when the operator rocks

the frame 119 in the direction indicated by the arrow *t*, or in the direction for starting the machine, the forward end of the lever 131 will be rocked downward, thus permitting the spring 91 to force the presser 70 90 into contact with the fabric, and when, by the resiliency of the spring 126, the frame 119 is rocked in the opposite direction, or in the direction for arresting the action of the machine, the lever 131 will be rocked in the 75 direction for elevating the cloth-presser, in opposition to the action of the spring 91.

135 represents the needle-thread take-up lever pivotally secured to the underside of the bed-plate 1 by screw 136 and actuated in 80 the usual manner from the take-up cam 137 carried by the main shaft, the sewing thread being directed from the supply to the thread-check 138, thread-tension 139 take-up guide-eye 140, and through the leaders, as 141, and 85 roller guide 142 to the needle eye.

In the operation of the machine, supposing the production to be the finishing of buttonholes, the operator places the shoe vamp in which the buttonholes have been worked upon the guide-plate 143 mounted on the front slide plate 144, with the loose threads lying between the successive buttonholes in contact with said last mentioned plate, and in such position as to cause the threads to pass between angularly arranged guiding elements, as 145, thus insuring that the lateral movements of the needle will alternately form blind stitches in the vamp 100 at opposite sides of said threads as the vamp is fed beneath the presser-foot and fabric-bender.

146 represents one form of commonly employed back slide plate.

It will be readily understood that the needle is actuated to enter and emerge from the same side of the vamp.

What I claim is:—

1. In a sewing machine of the character described, the combination with stitch-forming and cloth-feeding mechanism including a loop-taker shaft provided with a loop-taker, a needle, a needle-carrying bar and needle-plate, the latter provided with a bracket having a needle opening into which the needle passes before entering the fabric, and means for forming bends in the latter, of a needle-guard, a bracket sustaining said needle-guard and pivotally suspended below the needle-plate, and operative connections including a bell-crank lever between said bracket and said loop-taker shaft to move said needle-guard into effective relationship with the needle at a predetermined point in its movements to form stitches.

2. In a sewing machine of the character described, the combination with stitch-forming and cloth-feeding mechanism including a loop-taker shaft provided with a loop-taker, a needle, a needle-carrying bar and

needle-plate, the latter provided with a detachable bracket having a needle-opening into which the needle passes before entering the fabric, and means for forming bends in the latter, of a needle-guard, a bracket sustaining the latter pivotally suspended below the needle-plate, and operative connections including a bell-crank lever between said bracket and the loop-taker shaft to move
5 said needle-guard into effective relationship
10

with the needle at a predetermined point in its movements to form stitches.

In testimony whereof, I have signed my name to this specification, in the presence of two subscribing witnesses.

JOHN S. FINCH.
